UNITED STATES PATENT OFFICE.

MAURICE N. CONNOR, OF BUFFALO, NEW YORK, ASSIGNOR TO FRANK W. CARTER, OF BUFFALO, NEW YORK.

FIRE-EXTINGUISHER.

1,129,850.

Specification of Letters Patent.

Patented Mar. 2, 1915.

Application filed September 30, 1911. Serial No. 652,063.

To all whom it may concern:

Be it known that I, MAURICE N. CONNOR, a citizen of the United States, residing at Buffalo, in the county of Erie and State of New York, have invented a new and useful Improvement in Fire-Extinguishers, of which the following is a specification.

This invention relates to improvements in fire extinguishers of that type which are adapted to contain a fire extinguishing liquid or gas under high pressure.

The object of this invention is to provide a fire extinguisher of this type of simple and economical construction which will be strong and durable and be provided with tight fitting joints so as to prevent the leakage of the material contained therein, and which will have its parts so constructed and arranged that they can not easily become broken or disarranged.

In the accompanying drawings: Figure 1 is a fragmentary sectional elevation of a fire extinguisher embodying the invention. Fig. 2 is a sectional elevation, on an enlarged scale, through the head and upper end of the extinguisher. Fig. 3 is a fragmentary longitudinal section, on an enlarged scale, through the joint between the collar of the extinguisher and its head. Fig. 4 is a fragmentary cross-section in line 4-4, Fig. 2.

Like reference characters refer to like parts in the several figures.

The fire extinguisher comprises a hollow cylindrical, seamless body portion or casing A of copper or suitable material which is closed at one end by a bottom a firmly fitted within and soldered to the walls of the casing and at its opposite end has its sides drawn inwardly to form a neck portion a' having a central opening in which is arranged an annular collar B which fits snugly therein and projects above the neck portion of the casing.

The collar B is provided at its lower edge with an outwardly extending flange b, the upper face of which conforms in shape with and is adapted to fit snugly against the under or inner surface of the neck portion a' around its opening, and the under side of this flange has a depressed portion b' which is adapted to be filled with solder when the collar is secured to the casing for sealing the joint between the flange and the casing.

The collar B is externally screwthreaded above the neck of the casing and is provided

with a lock nut C which is adapted to engage the upper face of the neck portion of the casing and clamp the flange b of the collar firmly against the under side of the neck. This serves to secure the collar firmly to the casing and hold the same in place thereon. After the collar has been thus secured, it is desirable that the flange of the collar be thoroughly sweated and soldered to the casing. A very tight and secure joint is thus produced and the collar is enabled to withstand severe strains without disturbing or opening the joint between the collar and the casing.

D represents the head of the extinguisher which is provided on its inner or bottom side with an annular depending flange d which is adapted to fit over the collar B and have threaded engagement therewith for securing the head to the casing. On its inner side, adjacent to and within the flange d, the head D is provided with an annular channel d' of a width equal to the thickness of the collar B, and this channel is filled with a suitable packing d² of lead or other packing material. When the head is screwed down firmly in place on the collar B, the upper edge of the collar is forced into this packing and forms a tight fitting joint therewith. The upper edge of the collar is preferably provided with annular grooves d³ and the pressure of the collar on the packing forces the latter into these grooves so that a joint is formed through which it is impossible for the gas or liquid of the extinguisher to escape.

The head D is provided with a central valve chamber E which communicates by a passage e with an opening in the under side of the head in which is secured a stand pipe F which is open at its lower end and extends nearly to the bottom of the casing. In the valve chamber E is arranged a valve G for the controlling passage e, the wall of the passage at its upper end forming a seat for this valve. The valve G has a valve stem g which has screwthreaded engagement with the head and extends up through an opening g' therein, and is provided at its upper end with an annular handle g² for turning the valve to move it toward and from its seat. Any suitable means may be employed for packing this valve stem to prevent the escape of gas or liquid through the opening in the head through which the valve stem ex-

tends. In the construction shown, the head is provided on its upper face, adjacent to the opening g' , with an annular flange H within which is placed a suitable packing h which surrounds the valve stem and is arranged between packing rings h' . A nut h^2 , which has screwthreaded engagement with the outer face of the flange H , serves to force the packing firmly against the valve stem and hold it in place.

The valve G and its stem g are provided with a passageway I which extends from the lower end of the valve to the upper end of the stem, where it communicates with a gage or pressure indicator K of suitable construction which is secured to the upper end of the valve stem within the valve operating handle g^2 . The passageway I affords direct communication between the interior of the casing and the gage so that the latter will always register the pressure of the gas or liquid in the casing. By placing this passage within the valve itself, the construction is greatly simplified and the expense thereof considerably reduced. Further, no additional joints with their necessary packing are required, as would be the case if a separate connection were provided between the gage and the casing, and this reduces the possibility of leakage from the casing, simplifies the construction and greatly lessens the cost of manufacture, and protects the connection between the gage and the casing. The valve handle g^2 surrounds the gage K and projects a short distance above the same and forms a guard for the gage which prevents the gage from being broken or damaged in handling the extinguisher.

The head D is provided with an annular handle L which surrounds the valve handle g^2 and projects above the same. The handle L protects the valve handle and forms a base upon which the extinguisher can rest when inverted. The handle can be used in screwing the head in place on the collar B and in moving the extinguisher from place to place. A discharge passage M leads from the valve chamber E to the outer side of the head, and a suitable hose or other discharge connection may be secured in the outer end of this passage. The head may also be provided with a safety device m which is connected by a passage n with the interior of the casing. This device may be of any

suitable construction so arranged that when the pressure of the contents of the extinguisher exceeds a certain fixed point, it will permit the contents to escape and thus prevent undue strain upon the parts of the extinguisher.

In the construction shown, the extinguisher is intended to contain liquid and gas under high pressure but it may be used for either separately, if desired. The number of joints through which a possible leakage may occur is reduced to a minimum and the connections at the joints are so constructed as to possess great strength and rigidity and prevent the seams or joints from tending to open under any strain to which the parts may be subjected. The head is compact and its valve and gage are so protected that there is little danger of their becoming broken or disarranged in handling the extinguisher.

I claim as my invention:

A head structure for fire extinguishers comprising an integral casting having an annular handle projecting therefrom, said head having an opening extending therethrough in an axial direction, with an intermediate lateral discharge, a stand pipe secured in said head at the lower end thereof and in communication with said opening, a valve seat forming a part of said casting and arranged within the opening between the lateral discharge and the stand pipe, a valve coöoperating with said valve seat, a stem forming a part of said valve and threaded into the casting above the lateral discharge, said valve and valve stem having a longitudinally disposed opening, a stuffing box connection forming a part of the casting and projecting upward within the handle above the upper part of the casting, a suitable packing gland nut and gland ring coöoperating with said stuffing box connection, a valve handle of cup shape engaging said stem, and a gage connection secured to said stem and holding said valve handle in place, said cup-shaped handle serving to receive the gage.

Witness my hand this 23rd day of September, 1911.

MAURICE N. CONNOR.
